UNITED STATES PATENT OFFICE

JOHANNES RADLOFF, OF BERLIN, GERMANY, ASSIGNOR TO THE FIRM ALLGEMEINE ELEKTRICITATS-GESELLSCHAFT, OF BERLIN, GERMANY

ENGINE CYLINDER

Application filed December 23, 1927, Serial No. 242,123, and in Germany December 29, 1926.

My invention relates to internal combustion engines and is applicable with particular advantage to two-stroke cycle engines. It is an object of my invention to subdivide the engine frame supporting the cylinders as well as the cylinders themselves and other parts connected therewith in such manner as to render these parts capable of expanding more freely under the action of heat than is possible in similar engines hitherto designed.

In the practice of my invention I divide the frame supporting the cylinders in the longitudinal direction in order to render it capable of taking up the cylinder which is provided with a cooling jacket and is divided in the transverse direction, a middle piece forming the connection between the two halves of the cylinder and having a larger diameter than the cylinder. Conduits for the scavenging air and exhaust ports are arranged in the middle piece.

In order that the parts of the cylinders with the water jackets and the middle piece be capable of expanding freely independently from each other and from the supporting frame, the liners of the cylinders are provided at their ends with strong flanges, by means of which they rest on the supporting frame and are attached to the latter by the aid of pressing rings, while the middle piece rests upon special projections of the frame and the water jackets are connected to the liners of the cylinders only on the one side, so that a mutual displacement of the different parts is possible.

In the drawings affixed to this specification and forming part thereof an engine embodying my invention is illustrated diagrammatically by way of example.

40 In the drawings:

Fig. 1 is an elevation of a built-up cylinder block with the front frame portion partly broken away from the cylinder at the right,

Fig. 2 is a plan view of the block, partly in section on the line 2-2 in Fig. 1,

Fig. 3 is an elevation of the rear half of the frame in which the cylinders are held, with the cylinder at the left in axial section,

Fig. 4 is a section on the line 4-4 of Fig. 2,

50 Fig. 5 is a section also on the line 4-4 in

Fig. 2 showing a modified design of the cylinder head.

Referring first to Figs. 1-3, each of the two cylinders illustrated with its piston o' and its piston rod o'' is built up from two liners k and k at the top and the bottom of the cylinder and a central part e for the reception of passages f for the scavenging air and passages g for the exhaust, o is the upper and o''' is the lower cylinder cover, the latter being equipped with a stuffing box for the piston rod o'' . The several parts are held in proper position with respect to each other by the supporting frame for the cylinders which is divided in its longitudinal direction and its halves a and b are connected to each other by means of transverse bolts c . In order to relieve the transverse bolts c of shearing stresses, wedges d are inserted at the joint of the cylinder block which has been illustrated with part of the adjacent cylinder block B . The blocks are provided with flanges l' and connected by screws l at the joint. The liners k are surrounded by water jackets h and the central part e is surrounded by a water jacket e' and tubes i are secured to either end of the central part and telescoped into the jackets h for expansion. Each part of the frame is provided with apertures a' and b' , respectively, in which the flanged ends of the passages f and g are arranged, as shown for the air passage f in Fig. 1. In multi-cylinder engines each half of the frame may be formed in such a manner, that it is appropriate for the reception of several cylinders. In the example shown in the drawing the halves a and b of the frame serve for the reception of two cylinders. The connection of the two halves of the frame is effected by screws l .

The liners k of the cylinders are formed with strong flanges k' with which they rest on the frame and are secured to it by pressing rings m and screws n . The cylinder covers o o''' are fixed directly to the flanges of the liners by means of screw bolts p . Owing to this arrangement the piston forces are transmitted from the cylinder covers by the flanges of the liners k and the pressing rings m directly to the frame. The halves a and b

b of the frame are further provided with projections *q*, on which is fixed the central part *e* of the cylinder into which the liners *k* are inserted from above and below, the joint between the parts being packed by means of self-expanding piston rings *r* and stuffing boxes *s*. In this manner the piston-swept part of the cylinder is built up from the liner *k* at either end and from the inner wall of the central part *e* between the liners.

10 The parts *h* and *i* of the water jackets which are secured to the liners *k* and to the central part *e*, and connected with its cooling jacket *e'*, respectively, are guided in one another for telescoping movement and are packed by means of stuffing boxes *t*, the parts *i* being thus enabled to be shifted for the controlling and exchanging of the inner stuffing boxes *s*. By this arrangement, which may be 15 employed also in connection with undivided frames, the cylinder portions with the water jackets and the central part are enabled to expand freely independently from each other and from the supporting frame.

20 The cylinder system is assembled by first securing one of the two halves, for example the part *b* of the frame, to the posts *u* and the bed plate by means of stay rods *v*. Then the previously assembled parts of the cylinder are 25 pushed from the side towards the part *b* of the frame. Now the part *a* of the frame is brought in position from the side also, is connected to the part *b* by means of screws *c* and secured to the bed plate together with the posts *u* as described with reference to part *b*. The cylinders are then fixed to the frame also by the clamping rings *m*, whereupon the cylinder covers are fixed in place.

30 It will be understood that the central part *e* is supported by the projections *q* at its lower end and is free to expand in upward direction, this being permitted by the telescoping connection of the parts *h* and *i* of the jacket.

35 I may however also arrange the water jacket, liner and cylinder cover in such a manner, that as illustrated in Fig. 6, the water jackets *h* are provided with flanges *x* at their upper ends which is supported on a shoulder of the frame *a*, *b*, and that the flange *k'* of the corresponding liner *k* is supported on a shoulder of the jacket. The washer *m* is secured on the top of the frame for each cylinder and is preferably held thereon by the stays *v* and the cylinder covers *o* and *o''* are secured to the washer *m* by the screws *p*. The cylinder covers are shouldered near their lower ends and abutted on corresponding shoulders of the adjacent liners *k* so that the parts of the system are held together by the 40 pressure exerted thereon by the cylinder covers *o*, *o'''*, which are forced down upon the ends of the liners *k* by means of screws *p*.

45 I thus succeed in removing the cylinder cover either by taking off the nuts of the screws *p*, so that the piston can be withdrawn,

or by removing the supporting ring together with the cylinder cover by unscrewing the nuts of the stay rods *v*, so that the liner *k* and water jacket *h* can be withdrawn also. In this case the connection between the cylinder cover *o* and the supporting ring *m* need not be severed. If a reliable packing of the cooling space between the water jacket and the liner should not be obtained by the pressure exerted by the cylinder cover, a stuffing box *z* may be arranged between the flanges *x* and *k'* which is also readily accessible after the removal of the ring *m*.

50 This construction enables an easy erection and dismantling of the several parts, the control of the important joints of the pistons and the like without requiring any great dismantling work, and all the parts are free to expand.

55 I wish it to be understood that I do not desire to be limited to the exact details of construction shown and described for obvious modifications will occur to a person skilled in the art.

60 I claim:—

65 1. Engine comprising a working cylinder and a frame arranged to support said cylinder, said frame being divided longitudinally and each half of said frame being formed with an aperture facing the central part of 70 said cylinder.

75 2. Engine comprising a working cylinder in three parts including two end pieces and a central part and a frame arranged to support said cylinder, said frame being divided longitudinally and each half of said frame being formed with an aperture facing the central part of 80 said cylinder.

85 3. Engine comprising a working cylinder in three parts including two end pieces and a central part and a frame arranged to support said cylinder, said frame being divided longitudinally and each half of said frame being formed with an aperture facing the central part of 90 said cylinder, the three parts of said cylinder being independently mounted on 95 said frame for free relative expansion.

100 4. Engine comprising a working cylinder in three parts including two end pieces and a central part and a frame arranged to support said cylinder, said frame being divided longitudinally and each half of said frame being formed with an aperture facing the central part of 105 said cylinder, a cooling jacket surrounding each end piece.

110 5. Engine comprising a working cylinder in three parts including two end pieces and a central part and a frame arranged to support said cylinder, said frame being divided longitudinally and each half of said frame being formed with an aperture facing the central part of 115 said cylinder, a cooling jacket surrounding each end piece, a cylinder cover arranged to act with axial pressure on one 120

of said end pieces, said end piece resting on said central part.

6. Engine comprising a working cylinder in three parts including two end pieces and a central part and a frame arranged to support said cylinder, said frame being divided longitudinally and each half of said frame being formed with an aperture facing the central part of said cylinder, a cooling jacket surrounding each end piece, an inwardly flanged ring secured to an end face of said frame, a cylinder cover arranged to act with axial pressure on the inner flange of said ring, said end piece resting on said jacket and said jacket resting on said central part.

15 7. Engine comprising a working cylinder in three parts including two end pieces and a central part and a frame arranged to support said cylinder, said frame being divided longitudinally and each half of said frame being formed with an aperture facing the central part of said cylinder, said central part being of greater width than said end pieces and being formed with exhaust and 20 scavenging air ports, and projections formed 25 on said frame within said apertures to support said central part.

8. Engine comprising a working cylinder in three parts including two end pieces and 30 a central part and a frame arranged to support said cylinder, said frame being divided longitudinally and each half of said frame being formed with an aperture facing the central part of said cylinder, a cooling jacket 35 being secured at one end to each end piece, the free ends of said jackets being capable of expanding independently of said end pieces.

9. Engine comprising a working cylinder 40 in three parts including two end pieces and a central part and a frame arranged to support said cylinder, said frame being divided longitudinally and each half of said frame being formed with an aperture facing the 45 central part of said cylinder, a cooling jacket being secured at one end to each end piece, the free ends of said jackets being capable of expanding independently of said end pieces, tubes on said central part extending into gliding contact with said jackets and means for 50 packing said central part on said end pieces, said packing being arranged within and being accessible after displacement of said tubes.

55 In testimony whereof I affix my signature.
JOHANNES RADLOFF.
